OF GERMANY.

SUPERHEATER ELEMENT FOR FLUE-TUBE BOILERS.

1,208,405.

Specification of Letters Patent. Patented Dec. 12, 1916.

Application filed October 2, 1915. Serial No. 53,855.

To all whom it may concern:

Be it known that I, PETER THOMSEN, a citizen of the German Empire, residing at Cassel, Germany, have invented certain new and useful Improvements in Superheater Elements for Flue-Tube Boilers, of which the following is a specification.

My invention relates to superheaters for flue tube boilers in which suitable looped pipes or superheater elements are inserted in some or all of the flue tubes; steam flowing from the boiler to the engine, through these pipes, is superheated by the hot gases passing through the flue tubes.

More particularly my invention relates to the use of a plurality of parallel connected loops in a single flue tube. Elements so constructed afford a large cross section for the passage of steam, but have the disadvantage that the superheated ends of the elements afford a large surface of contact to the flue gases passing from the end of the flue tube into the smoke box which flue gases have already largely lost their heat to the superheater pipes; as a consequence there is an actual heat transfer from the superheated element ends to these flue gases, the magnitude of the same being dependent upon the temperature difference.

According to the present invention the above mentioned disadvantage is avoided, without diminishing the necessary and advantageous cross section of the pipes, by causing the several parallel connected tube loops to be united on the superheated steam side, to a common exit pipe having a cross section equal to the sum of the cross sections of the individual pipes. By choosing a suitable location for the joint between the individual ends and the exit pipe, inside of the flue tube, there also results the possibility of making the superheating of the steam independent of the final temperature of the flue gases, within practical limits at any rate, since the heat transfer will become quite small by reason of the lessening of the surfaces involved which is thus brought about. In order, further, to lessen the number of connections between the elements and the steam collectors, or headers, as also to make the number of such connections for superheated and wet steam ends equal, I may also join the saturated steam ends of the parallel

elements to a common collecting or inlet pipe having a section equal to the sum of the individual pipes.

My invention will be better understood by referring to the accompanying drawings in which—

Figure 1 shows diagrammatically, a pair of parallel connected superheater elements, according to the known art, in a single flue tube each element comprising two individual parallel pipes; Figs. 2 and 3 show, also diagrammatically, superheater elements according to my invention in two different embodiments; Fig. 4 is a vertical longitudinal section through a flue tube containing an element constructed according to the diagram of Fig. 3; Fig. 5 is a front view of Fig. 4; Fig. 6 is a cross section through Fig. 4 along the line 6—6; Fig. 7 is a similar cross section along the lines 7—7 of Fig. 4; and Fig. 8 is a vertical longitudinal section through a flue tube containing another embodiment of my invention.

In the known arrangement, shown in Fig. 1, there are two parallel U-shaped pipe loops *a* and *b* in the flue tube *c* so that the steam to be superheated flows into the stream of flue gases and then back again; as the steam enters the flue tube its direction of flow is contrary to that of the flue gases and as it leaves the flue tube its direction is the same as the flue gases. In the first, or saturated, portion of the element the amount of heat absorbed is very great, because the temperature difference between the outgoing flue gas and the incoming wet steam is itself great. On the other hand in the last, or superheated, part of the element there is no longer any absorption of heat by the steam but, on the contrary, it may even happen that the superheated steam will itself lose heat to the flue gases because said gases, at their exit into the smoke box, will have a temperature less than that of the superheated steam. Upon the assumption that the temperature of the flue gases at exit is about 300° C., that of the steam on the saturated steam side of the element about 190° C., and that of the steam on the superheated steam side of the element about 350° C. there will be, at about the center of the superheated steam part of the element, substantially no heat absorption since the tem-

perature difference between the flue gases and steam at this point will only be about 20° C. At the exit end of the element there is not only a failure to further superheat the steam, but the superheated steam actually gives back a certain amount of heat to the flue gases. With a higher degree of superheat, say to about 400° C. this effect becomes even more important.

10 Elements made according to my present invention, as shown in Figs. 2 and 3, avoid the above disadvantages. An element according to Fig. 2 comprises two parallel U-shaped loops *d* and *e*, each having a return bend *g*, with their superheated ends opening into a common exit pipe *f* of cross section equal to the sum of the cross sections of the individual pipes *d* and *e*. The point at which pipe *f* joins the individual pipes *d* and *e* is placed well within the flue tube *c*.

15 In the form of my invention shown in Fig. 3 the saturated steam ends of the two loops *j* and *k* are also connected to a common pipe *m* through which saturated steam enters the elements. The junction point, *n*, between pipe *m* and the saturated steam ends is located at the smoke box end of the flue tube in order that the heat of the out-flowing flue gases may be employed upon as 20 large a heating surface as possible. This junction point of the saturated steam ends with the inlet pipe may, conveniently, be placed entirely outside of the flue tube end in the smoke box in order that on this side 25 where the steam temperature is relatively low, all the pipe lengths may be passed over by the hot gases as they ascend in the smoke box. The superheated steam sides of the individual loops are shorter than the saturated 30 steam sides so that the common exit tube *o* extends well into the flue tube; the actual distance to which the tube *o* extends in the flue tube may be varied according to the 35 temperature of the gases flowing from the flue tube. In this way the superheated surfaces capable of giving off heat are made 40 smaller. This form of element affords the further advantage that, in spite of there being four loop lengths within the flue tube 45 each element has but two ends which must be united to the steam collectors.

50 Since the superheated steam end of an element, according to the invention, requires less space inside the flue tube than would be required by the ends of individual loops having the same cross section, the space thus gained may be partially utilized by insulation surrounding the superheated end, thus still further diminishing the eventual heat 55 loss from the superheated steam end.

An element such as has been described may be so constructed that each loop *j* and *k* is arranged in a horizontal plane in the smoke tube *c*, as shown in Figs. 4 to 7. In 60 this construction the two terminal pipes *m*

and *o*, as they emerge from the smoke tube, are also arranged in a horizontal plane.

Fig. 8 shows another modification in which the two loops *r* and *s* are in two parallel vertical planes; the terminal tubes *m* and *o* are also in a single vertical plane, one under the other.

The individual looped pipes which are used to constitute one of my improved elements, as above-described, may also take the 7 form of a plurality of series connected loops, each loop being in a different flue tube; in this case the outlet tube will be attached to the last or end loop.

The joining of the ends of the two loops 8 with the terminal tubes may be accomplished either by welding or the equivalent or through the use of special connecting pieces such as are shown, *e.g.*, in German Patent No. 274,603.

Having described my invention, I claim:

1. In a boiler provided with flue tubes, a superheater element comprising a plurality of completely independent parallel U-shaped loops inserted in some of the flue 9 tubes, the superheated ends of the loops being connected to a common exit pipe having a cross section substantially equal to the sum of the cross sections of the individual pipes.

2. In a boiler provided with flue tubes, a superheater element comprising a plurality of completely independent parallel U-shaped loops inserted in some of the flue tubes both the superheated ends and the saturated ends of the loops being connected respectively to common exit and inlet pipes having cross sections substantially equal to the sum of the cross sections of the individual pipes.

3. In combination with a boiler provided with flue tubes and a smoke box, a superheater element comprising a plurality of completely independent parallel U-shaped loops inserted in some of the flue tubes, both the superheated ends and the saturated ends of the loops being connected respectively to common exit and inlet pipes having cross sections substantially equal to the sum of the cross sections of the individual pipes, the connecting point of the superheater ends being within a flue tube and of the saturated ends within the smoke box.

4. The combination, with a locomotive boiler flue, of two parallel U-shaped steam superheating tubes arranged within said flue and consisting each of a long leg and of a short leg, means to conduct saturated steam simultaneously into the ends of the two long legs, a connection between the ends of the two short legs, and a third tube connected with said connection and adapted to lead off the steam superheated within said two U-shaped tubes.

5. The combination, with a locomotive boiler flue, of two parallel U-shaped steam superheating tubes arranged within said

flue and consisting each of a long leg and of a short leg, a connection between the ends of the two long legs; means to conduct saturated steam into said connection, a connection between the ends of the two short legs, and a third tube connected with said second connection and adapted to lead off the steam superheated within said two U-shaped tubes.
